UNITED STATES PATENT OFFICE.

HARRY K. KOPPIN, OF JACKSON, MICHIGAN, ASSIGNOR TO GENERAL MOTORS CORPORATION, OF DETROIT, MICHIGAN, A CORPORATION OF DELAWARE.

PAINT-DRYING MACHINE.

Application filed March 8, 1923. Serial No. 623,817.

To all whom it may concern:

Be it known that I, HARRY K. KOPPIN, a citizen of the United States of America, and a resident of Jackson, county of Jackson, 5 and State of Michigan, have invented certain new and useful Improvements in Paint-Drying Machines, of which the following is a full, clear, concise, and exact description, such as will enable others skilled in the art 10 to which the invention relates to make and use the same, reference being made therein to the accompanying drawings, which form a part of this specification.

This invention relates to devices for drying protective coverings or coatings on manufactured articles and has reference 15 more particularly to the drying of paints, varnishes, or enamels on wheels and other elements of motor vehicles.

One of the objects of the invention is the provision of a device for drying paints, varnishes, enamels, etc., which will occupy a minimum space and at the same time is adapted to treat articles on quantity production with a minimum amount of manual 20 labor.

Another object of the invention is the provision of means for hastening the operation of drying the protective covering of articles 25 by the application of heat thereto.

A further object of the invention is the provision of means for drying the protective covering on articles in the presence of a current of air, whereby the drying operation 30 is more effectively and expeditiously accomplished.

A still further object of the invention is the provision of an endless carrier with loading and unloading stations located adjacent 35 to each other whereby the full length of the carrier is utilized during the paint drying operation.

Another object of the invention is the provision of means for rotating the articles 40 during the paint drying process whereby the paint is maintained evenly distributed over the surface of the article during the drying operation.

Other and further objects and advantages of the invention will appear as the description proceeds. 50

On the drawing which shows a paint drying device more or less diagrammatically, Figure 1 is a side elevation of the drying device with parts broken away and parts in 55 section.

Figure 2 is a front elevation thereof with parts in section and parts broken away.

Figure 3 is a detailed view of a slightly modified form of the operating mechanism, 60 and

Figure 4 is a detailed view of a clutch mechanism used in connection with the paint drying device.

In the painting of articles that are manufactured in quantities, as for instance in the painting of wheels in the automobile industry, it has heretofore been necessary to devote a very large portion of the floor space to this work. In some plants as much 70 as 8,000 or 9,000 square feet of floor space is necessary for this purpose. I have found, however, that by employing an endless carrier and arranging the carrier to operate in a vertical plane that a drying device for 75 protective coverings for articles may be constructed that will occupy a minimum amount of floor space in the present instance about 250 sq. ft. and that the device will operate as efficiently and perform the work 80 equally as well as do the present devices that occupy a floor space of many times this size.

On the drawing, the reference character 85 10 designates an endless carrier which in the present instance is more or less circular in form and is wheel like in appearance. It consists of the hub 11 mounted rigidly on the axle 12. Inner and outer spokes 13 and 14 extend radially outwardly from said hub 90 and are connected together by the cross members 15 at the outer ends thereof. Braces or truss members 16 and 17 at each side of the carrier connect the corresponding spokes together as clearly shown in 95 Figure 2 of the drawing and hold the spokes

at each side of the carrier in spaced relation. Suitable cross braces are also provided.

Suitable members are provided for supporting the endless carrier in its operative position. For the purpose of this disclosure the carrier is shown as being in a vertical plane. The shaft 12 is journaled in bearings 19 and 20 which are mounted on suitable supporting members 21 and 22 located at the rear and in front of the carrier member 10. The supports 21 and 22 may be secured to the floor 18 in the usual or any well known manner.

The endless carrier is preferably provided with article supporting members. These members may be arranged in any suitable manner but preferably they are rotatably mounted on the carrier 10. As shown, these supporting members are in the form of shafts or spindles 23 and 24. In order to economize space these shafts may be arranged in staggered relation as clearly shown in Figure 2 of the drawing. The shafts 23 are mounted in journals at the periphery of the endless carrier 10, while the shafts 24 are mounted in journals which in turn may be carried by the struts 17 or by any other suitable portion of the carrier inwardly of the shafts 23.

Where the device is to be employed for the purpose of drying paint on automobile wheels these shafts or spindles 23 and 24 may extend laterally beyond the front face of the carrier and are adapted to have a series of the freshly painted wheels 25 mounted thereon. Suitable spacers 26 hold the wheels in spaced relation. The wheels are held on the shafts or spindles by suitable means such as the nuts 27 (see Figure 1).

The endless carrier 10 is adapted to be rotated by any suitable means either manually or by power operated devices. Moreover, the spindles or shafts 23 and 24 are adapted to be rotated on their axes independently of or in conjunction with the rotation of the endless carrier on its axis. The spindles or shafts 23 and 24 are rotated in order that the protective fluid may not "run" or collect on any particular part or point on the wheel during the drying operation.

As shown on the drawing the carrier is rotated by a motor 28 through the mechanism that will now be described. A belt 29 engaging a pulley 35 on the motor 28 operates the pulley 36 which is rigidly secured to the shaft 37 (see Fig. 4) which in turn is journaled in suitable supports 38 and 39 located at the base of the machine. A pulley 41 loosely mounted on the shaft 37 is provided with one member of a clutch 42 which is adapted to engage the other member of the clutch 42, carried by the pulley 36. The pulley 41 is adapted to be shifted

by any suitable means such as by means of the lever 44. The lever 44 may be provided with cord 45 by means of which the clutch may be operated at a distance. A belt 46 engaging the pulley 41 is adapted to rotate the pulley 47 which is rigidly secured to the worm shaft 48 which in turn is adapted to rotate the worm gear 49 rigidly mounted on the shaft 12 of the carrier. It will thus be apparent that when the motor 28 operates and the clutch 42 is thrown into operative position the shaft 12 will rotate thus causing the endless carrier to rotate in like manner. The relative sizes of the pulleys and the worm gears are such that the endless carrier rotates very slowly. In the actual use of the device the carrier will rotate in from 20 to 40 minutes. Its speed, of course, will depend on the relative sizes of the pulleys and gears as well as upon the R. P. M. of the motor. But the parts are so adjusted that sufficient time is given for drying the protective covering on the articles during one rotation of the carrier.

Suitable means are provided for causing a circulation of air about the painted articles during the rotation of the carrier. Preferably the air circulating means is so arranged that the air in circulating forms a continuous circuit. It is understood, however, that this arrangement is not necessary to the operation of the device and it is understood that this invention is not limited to such construction.

In order to efficiently accomplish the proper circulation of the air, a closed passageway is provided through which air is circulated and within which the movements of the articles are confined. As shown on the drawings, a passageway 51 is provided. This passageway comprises the front wall 52 which may extend across the front face of the carrier from the top thereof to the floor 18; an outer wall 53 extending about the carrier; and an inner wall 54 secured in the circular opening 55 formed in the front wall 52. The rear wall of the passageway is formed by a plate 56 rigidly secured to the carrier 10 and is rotatable therewith. It will thus be seen that an annular passageway is provided around which the articles are adapted to travel.

An air conduit 57 leading from the fan 58 is adapted to deliver air to the passageway 51. While it is understood that the air may be delivered at any point about the passageway, but for convenience of illustration it is shown on the drawing as delivering the air to the top portion of said passageway. Means are provided for returning the air from the lower portion of the passageway to the fan 58. As shown, two conduits 59 and 61 connected with the lower portion of the passageway are adapted to deliver the air to the fan 58.

It will be noted that the passageway 51 is just large enough in cross section to accommodate the article supporting members 23 and 24 with the articles supported thereon. This insures the air properly circulating about them. The inner wall 54 greatly aids in this circulation in that it prevents the air from taking a straight course from the inlet conduit 57 directly to the exist conduits 59 and 61.

If desired suitable means may be provided for heating the air. As shown, the conduits 59 and 61 deliver the air into the chamber 62 in which may be located a heating element 63.

It will be observed, that by this arrangement, the warmest air is at the top of the passageway and that the articles are gradually heated as they near the top of the device and then by radiation they are gradually cooled as they pass from the top of the device to the removing station. Thus it will be seen, that the paint is partially dried before being subjected to the greatest heat thereby permitting the volatile constituents of the paint or varnish to evaporate before the outer surface becomes so hardened as to encase the same and thereby cause blisters or blow-holes in the paint and thus injuring the appearance and usefulness of the same.

In order to provide for the escape of noxious fumes the passageway 51 is provided with ventilator opening or passage 64 in which is mounted a damper 65 of any well known construction for regulating the size of the opening in the passage 64.

If desired suitable means may be provided for rotating the supports 23 and 24 during their travel around the passageway 51. Any suitable means may be provided for this purpose. As shown, the shafts or spindles 23 and 24 are provided with sprockets 66 and 67 about which the drive chain 68 engages. The chain is driven by the sprocket 69 loosely mounted on the shaft 12. An adjustable chain tightener 68^a maintains the proper tension on the chain 68. The sprocket 69 is provided with one member of a clutch 71, the other member of which is carried by the sprocket 72. The clutch is operated by the handle 73 to which a cord 74 may be attached for operating the same at a distance. The sprocket 72 is operated by a suitable chain from the sprocket 75 rigidly secured to the shaft 76 of the worm gear 77 which in turn is operated by the worm on the shaft 37, in the usual manner.

It will thus be seen that by operating the clutches 42 and 71 the spindles or shafts 23 and 24 and the carrier 10 may be rotated simultaneously or independently of each other.

A portion of the front wall 52 of the passageway 51 is removed as at 78 for the purpose of forming loading and unloading

stations for the articles that are being operated upon. If it is desired to have the loading and unloading stations separately located a similar portion of wall 52 may be removed as at 79 for this purpose. When 70 the station 79 is not employed the same way be covered by the plate 81 which may be held in position by any suitable means such as by means of the clips 82.

In the operation of the device, the clutches 42 and 71 are operated by suitable levers which in practice are located adjacent to the loading and unloading stations, but which for the purpose of clearness in disclosing the remaining operating mechanism 75 are not shown on the drawings.

In the modified form of the device shown in Figure 3 the sprocket 69^a for operating the spindles or shafts 23 and 24 is rigidly secured to the frame member 21, whereby 80 when the shaft 12 is rotated the spindles or shafts 23 and 24 will be caused to rotate upon their axes by the engagement of the chain 68 with said sprocket. In this arrangement of the device the spindles or 85 shafts 23 and 24 cannot, of course, be operated independently of the shaft 12.

If desired, the shaft 12 may be provided with a brake mechanism 83, of any suitable or well known construction. As shown in Figure 3, the shaft 12 is provided with a brake drum 84 having a brake band 85 for gripping the same. The brake band 85 is contracted in the usual manner by rotating the shaft 86. The shaft 86 may be rotated 90 in any suitable manner as by means of a foot pedal 87. When it is desirable to operate the device by gravity the station at 79 is employed as a loading station, and that at 78 as an unloading one. It will thus be seen that under those conditions the right hand side of the carrier as shown in Figure 2, being always full will be heavier than the left hand side and consequently the carrier will tend to rotate clockwise. By means of the brake 83 the carrier may be stopped at any desired position by the operator.

It is thought from the foregoing taken in connection with the accompanying drawings that the construction and operation of my device will be apparent to those skilled in the art, and that various changes in size, shape, proportion and details of construction may be made without departing from the spirit and scope of the appended claims.

I claim:

1. In a device of the class described, a circular carrier, a passageway for enclosing the same, means for rotating said carrier, supports on said carrier, means for moving said support relatively to said carrier, and means for circulating air in said passageway.

2. In a device of the class described, a rotating carrier, article supports mounted on said carrier and movable relatively thereto,

an enclosed circular passageway for said supports, and means for circulating heated air about said supports, said means comprising a fan and heater, an air conduit for conducting air from said fan and heater to said passageway and a conduit for conducting air from said passageway to said fan and heater.

3. In a protective covering drying device, 10 a rotatable wheel like carrier, supports extending laterally from said carrier, a circular passageway enclosing said supports, means for rotating said wheel-like carrier, means for rotating said supports on said carrier 15 and means for circulating air in said passageway said means comprising a fan, a conduit for conducting air from said fan to said passageway and a conduit for conducting air from said passageway to said fan.

4. In a device of the class described, a 20 wheel-shaped carrier rotatable about a horizontal axis, supports on said carrier extending laterally therefrom, a circular passageway enclosing said carriers, a heater, a fan 25 in communication therewith, a conduit leading from said fan to the top portion of said passageway, and two conduits connecting the lower portion of said passageway at each side thereof with said heater.

5. In a device of the class described, a carrier, article supporting members on said carrier, a passageway for enclosing said members means for progressively heating articles carried by said members for a portion of the 35 distance traversed by said members and for progressively decreasing the amount of heat the articles are subjected to during the remainder of the distance traversed by said supports.

6. In a paint drying device, an endless 40 carrier, a passageway, article supports mounted on said carrier and movable in said passageway, means for causing a circulation of air in said passageway, means for heating said air, said parts being so constructed and arranged that the articles carried by 45 said supports are progressively heated during a portion of their journey from their initial movement in said passageway.

7. A drier comprising, in combination, a 50 wheel-like carrier (10) for articles to be dried, inner and outer coaxial drum-like members (53 and 54) and end walls (52 and 56) defining an annular passageway 55 through which the articles are moved, and means for circulating air through said passageway.

8. Apparatus for treating wheels or the 60 like comprising, in combination, a rotatable wheel-like carrier, rotatable spindles for the wheels journaled on the carrier, mechanism for controlling the rotary movement of the carrier, and means for rotating the spindles.

9. Apparatus for treating wheels or the

like comprising, in combination, an angularly-movable carrier, spindles each arranged to support a plurality of wheels and all journaled on the carrier, operator-controlled means for indexing the carrier, and power-driven mechanism for rotating the spindles.

10. Apparatus for treating wheels or the like comprising, in combination, an angularly-movable carrier having axially separated parts, spindles for the wheels journaled in said parts and projecting laterally from the carrier parallel to the axis of the carrier, means at the free end of each spindle to hold on the spindle a plurality of wheels, means to control the movement of the carrier, and means to rotate the spindles.

11. Apparatus for treating wheels or the like comprising, in combination, an angularly-movable carrier having axially separated parts, spindles for the wheels journaled in said parts and projecting laterally from the carrier parallel to the axis of the carrier, means at the free end of each spindle to hold on the spindle a plurality of wheels, operator-controlled power mechanism to operate the carrier, and independently-controlled power mechanism to rotate the spindles.

12. Apparatus for treating wheels or the like comprising, in combination, an angularly-movable carrier having axially separated parts, spindles for the wheels journaled in said parts and projecting laterally from the carrier parallel to the axis of the carrier, means at the free end of each spindle to hold on the spindle a plurality of wheels, a housing forming an annular passageway including the spindles and wheels, and means for controlling the movement of the carrier to move the wheels around through the annular passageway.

13. A drier comprising, in combination, an endless carrier having article supports spaced about its periphery, a housing forming an annular passageway enclosing the supports, and means for introducing heated air into said passageway including an inlet opening in the housing, the drier being constructed and arranged to permit loading of articles on said supports some distance before the supports come opposite said inlet opening so that they will be heated gradually, and to permit unloading of the articles from said supports some distance beyond said inlet opening so that the articles may first have cooled gradually.

14. Apparatus comprising, in combination, a wheel-like carrier having article supports projecting from one side parallel to its axis, a plate secured to said side of the carrier and arranged perpendicular to said supports at their bases, substantially cylindrical walls respectively inside and outside the supports, and a fixed plate oppo-

site the plate on the carrier, the two plates and the two cylindrical walls forming a substantially closed housing defining an annular chamber containing the supports.

5 15. Apparatus comprising, in combination, a substantially circular rotatable carrier, inner and outer circular rows of sup-

ports on the carrier, the supports of one row being staggered with respect to the supports of the other row, means to control the movement of the carrier, and means for rotating the supports simultaneously.

In testimony whereof I affix my signature.

HARRY K. KOPPIN.
